[57] CLAIM

The ornamental design for fireplace, as shown and described.

DESCRIPTION

FIG. 1 is a perspective view of a fireplace, showing my new design;

FIG. 2 is a front elevational view thereof;

FIG. 3 is a right side elevational view thereof;

FIG. 4 is a top plan view thereof;

FIG. 5 is a left side elevational view thereof;

FIG. 6 is a rear elevational view thereof;

FIG. 7 is a bottom plan view thereof.

The broken line disclosure of a stove pipe in FIG. 1 and of door knobs in FIGS. 1 and 2 is for illustrative purposes only and forms no part of the claimed design.

FIG. 1.

FIG. 2.

FIG. 3.

FIG. 4.

FIG. 5.

FIG. 6.

FIG. 7.
